(57) **CLAIM**

The ornamental design for a grassed decoy weight, as shown.

DESCRIPTION

FIG. 1 is an environmental front and left side perspective view of a grassed decoy weight attached to a decoy showing my new design.

FIG. 2 is a left side view thereof;

FIG. 3 is a right side view thereof;

FIG. 4 is a front view thereof; and,

FIG. 5 is a top view thereof.

The broken lines depict environmental structure and are for illustrative purposes only and form no part of the claimed design.

1 Claim, 5 Drawing Sheets

Fig. 1 Front and Side View

Fig. 2 Left Side View #2

Fig. 3 Right Side View

Fig. 5 Top View
